CLAIM

The ornamental design for a golf bag with partitions for clubs, as shown and described.

DESCRIPTION

FIG. 1 is a front elevational view of a golf bag with partitions for clubs showing my new design;

FIG. 2 is a side elevational view thereof, the opposite side being a mirror image thereof;

FIG. 3 is a rear elevational view thereof;

FIG. 4 is a bottom plan view thereof;

FIG. 5 is a top plan view thereof showing my golf club partition design; and,

FIG. 6 is a perspective view thereof.
